DESIGN FOR A COMBINED MEDAL AND IDENTIFICATION TAG

Russell E. McKenna, Providence, R. I.

Application April 24, 1942, Serial No. 106,688

Term of patent 3½ years

To all whom it may concern:

Be it known that I, Russell E. McKenna, a citizen of the United States of America, residing in Providence, county of Providence, State of Rhode Island, have invented a new, original, and ornamental Design for Combined Medal and Identification Tag, of which the following is a specification, reference being had to the accompanying drawing forming a part thereof.

Fig. 1 is a front view of the combined medal and identification tag showing my new design; Fig. 2 is a rear face view thereof; and Fig. 3 is an edge view thereof.

I claim:

The ornamental design for a combined medal and identification tag, substantially as shown.

RUSSELL E. MCKENNA.
